UNITED STATES PATENT OFFICE.

MARY J. McARTHUR, OF CLEVELAND, OHIO.

WINDOW BOX.

Application filed September 6, 1923. Serial No. 661,252.

My invention relates to a window box adapted to hold foods and arranged to be disposed against a raised lower sash so that fresh air may enter beneath said sash and circulate through the box by reason of perforations in the walls of the box.

The general object of my invention is to provide a window box and associated devices which will permit of the box being positioned on the window sill directly against the lower rail of the raised lower sash, adjacent a side of the window and to provide means whereby a complete closure of the window may be effected to prevent drafts.

A further object of the invention is to provide a box for the indicated purpose, the construction of which will reflect practical considerations with respect to strength, simplicity and efficiency.

The nature of my invention, its characteristic features and advantages will clearly appear as the description proceeds.

Reference is to be had to the accompanying drawings forming a part of this specification, it being understood that the drawings are merely illustrative of one example of the invention.

Figure 1 is a perspective view of the invention emplaced in a window;

Figure 2 is a vertical section on an enlarged scale in a plane indicated by the line 2-2 in Figure 1;

Figure 3 is a longitudinal vertical section as indicated by the line 3-3, Figure 2;

Figure 4 is a horizontal section as indicated by the line 4-4, Figure 2;

Figure 5 is a horizontal section through the window frame showing my novel means for closing the window above the meeting rails to prevent draft when the box is emplaced against the raised lower sash;

Figure 6 is a perspective view of the closure means for the window above the meeting rail of the lower sash;

Figure 7 is a detail in transverse vertical section as indicated by the lines 7-7 in Figures 5 and 6.

In carrying out my invention in accordance with the illustrated example a box 10 is provided having a front door 11 here shown as a swing door. At the back of the box at one end is an extension back plate 12 having a finger-hold 13, said plate sliding through a slot in the adjacent end of the

box 10 and movable between the back 14 of the box and an inwardly directed flange 15 on said end of the box.

Within the box I provide a table 16 preferably of sheet metal as is the box 10. The table 16 is formed at the side edges with depending flanges 17, the flanges of adjacent sides being formed into legs 18 the lower ends 19 of which are made tubular and adapted to be passed downwardly through perforations in the false bottom 110 of the box 10 to rest on the fixed bottom 210. The false bottom 110 and the table 16 are removable to facilitate cleaning of said parts and the box body. The table 16 and the back 14 are also perforated to afford circulation of air.

To emplace the box the lower sash is raised and the box set on the window sill with its back directly against the lower rail of the raised lower sash. In order to effect a tight closure of the window with the box in position, I provide on the top of the box a closure plate 20 an end 21 of which is formed with members to enter between the jamb members of the window. A slide plate 22 is movable on top of the plate 20 in a guide 23 along the front edge of said plate 20. In the plate 22 there is a longitudinal slot 24 through which a bolt 25 passes, said bolt passing through the plate 20 and through the top of the box 10, the bolt at its upper end receiving a wing nut 26 for tightening the slide plate 22 in the adjusted position. Said slide plate 22 at its outer end 122 is formed with members corresponding with the jamb members to make a close fit against the jamb. The bolt 25 passes also through a transverse slot 27 in the top of the box 10 whereby the two plates 20, 22, and the bolt 25 may be together moved transversely of the box to cause the back edges of said plates to contact with the glass of the sash A, said back edges being downturned as at 121, Figure 2. With the plates 21, 22 engaging the opposite jambs and contacting with the glass of the lower sash and with the slide plate 12 moved to an outer position against the adjacent jamb, the opening formed by the raising of the sash is completely closed against drafts.

To support the box 10 in position brackets 28 of suitable design are fastened by screws or the like beneath the window sill as shown in Figures 2 and 3.

It becomes necessary in order to exclude drafts when the box 10 is emplaced as described, to effect a closure also of the window above the lower sash because in the 5 raised position of such sash, the meeting rails of the two sashes are separated. I therefore provide an assemblage as follows: The plate 29 has holes 30 to receive screws or other fasteners for fastening the plate 10 down to the top of the meeting rail *a* of the lower sash. A second plate 31 is also provided and formed with holes 32 to receive fasteners for securing said plate to the meeting rail *a*. The plates 29 and 31 are secured 15 to rail *a* at opposite sides of the sash fastener element B on said sash. Between the plates 29, 31 is a casing 33 to cover the sash fastener element B. Said casing is secured to one of the plates 29 and 31 in a manner 20 to permit the casing 33 to be swung into line with said plates and over the fastener element B or to be swung outward to a position to uncover fastener element B for manipulating the latter. The connection between 25 casing 33 and the element 31 is as follows: The casing 33 is formed with side flanges 35 overlapping the plates 29, 31 and through one of said flanges 35 is passed a vertical pivot pin 34 which passes through 30 a slot 36 in the plate 31, the arrangement permitting the casing 33 to be moved to its inner position or to the outer position and at the same time to insure its complete movement against the glass of the sash A. The 35 plates 29, 31 have weather strips 37 along the inner edges and similar strips 38 are provided on the casing 33. It will be noted that said casing as shown in Figure 2 is open at the bottom and back.

40 I would state in conclusion that while the illustrated example constitutes a practical embodiment of my invention, I do not limit myself strictly to the exact details herein illustrated, since, manifestly, the same can be considerably varied without departure 45

from the spirit of the invention as defined in the appended claims.

Having thus described my invention, I claim:

1. A window box adapted to be disposed 50 in a window frame in an opening below the lower sash when raised, and means mounted on the top of the box to effect an air tight closure between the box and the pane of the window sash and entirely across the window 55 opening at one side of the box, and a vertical plate adapted to close the space between one end of the box and the adjacent jamb, said vertical plate lying against and in parallel relation thereto within the box, 60 said box having a vertical slot through that end of the box through which said plate may slide, said vertical plate and the aforesaid means on the top of the box cooperating to completely close the space below the 65 window sash and the adjacent jamb.

2. The combination with a window box, of a fixed plate at one end on top of the box and adapted to contact with the window pane and the adjacent jamb, a slide movable 70 longitudinally on said fixed plate and adapted to engage the pane and be projected beyond the opposite end of the box, and means connecting said fixed plate and slide with the box top to permit a transverse movement of said fixed plate and slide.

3. A window box having a raised perforated and removable false bottom therein, and a separate and removable table having legs extending downwardly through said 80 false bottom and resting on the true bottom, whereby displacement of the table is prevented.

4. A window box having a perforated false bottom movably resting on the main 85 bottom of the box, and having substantially the same area and shape as the true bottom, and a table having legs engaging said false bottom for holding the table in position.

MARY J. McARTHUR.
